(57) **CLAIM**

The ornamental design for a lighting fixture as shown and described.

DESCRIPTION

FIGS. 1-7 are drawings of a first embodiment of the lighting fixture, in which:

FIG. 1 is a top perspective view;

FIG. 2 is a bottom perspective view;

FIG. 3 is a left side view;

FIG. 4 is a front view;

FIG. 5 is a right side view;

FIG. 6 is a top view; and

FIG. 7 is a bottom view.

FIGS. 8-14 are drawings of a second embodiment of the lighting fixture, in which:

FIG. 8 is a top perspective view;

FIG. 9 is a bottom perspective view;

FIG. 10 is a left side view;

FIG. 11 is a front view;

FIG. 12 is a right side view;

FIG. 13 is a top view; and

FIG. 14 is a bottom view.

FIGS. 15-21 are drawings of a third embodiment of the lighting fixture, in which:

FIG. 15 is a top perspective view;

(Continued)

FIG. 16 is a bottom perspective view;
 FIG. 17 is a left side view;
 FIG. 18 is a front view;
 FIG. 19 is a right side view;
 FIG. 20 is a top view; and,
 FIG. 21 is a bottom view.
 Broken lines in the drawings depict portions of the lighting fixture that form no part of the claimed design.

1 Claim, 9 Drawing Sheets
